DESIGN FOR A CLOTHESPIN BAG

Minnie A. Howard, Los Angeles, Calif.

Application November 12, 1948, Serial No. 149,584

Term of patent 14 years

(Cl. D87—5)

To all whom it may concern:

Be it known that I, Minnie A. Howard, a citizen of the United States, residing in the city and county of Los Angeles and State of California, have invented a new, original, and ornamental Design for a Clothespin Bag, of which the following is a specification, reference being had to the accompanying drawing, forming part thereof.

The figure is a front perspective view of a clothespin bag, showing my new design, the rear face of the bag being plain.

My design for a clothespin bag is characterized by the flap-covered opening on the front thereof located just beneath the horizontal strip across the bag below and parallel to the edge of the bag in association with the slightly smaller rectangular pocket member located at the bottom edge of the bag substantially below the flap member, all as shown.

I claim:

The ornamental design for a clothespin bag, as shown and described.

MINNIE A. HOWARD.
